United States Patent Office

Des. 193,345
Patented Aug. 7, 1962

193,345

TAPE CONSOLE

Karl R. Peterson, Phoenix, Ariz., assignor to General
Electric Company, a corporation of New York

Filed July 21, 1961, Ser. No. 66,013

Term of patent 14 years

(Cl. D26—14)

Fig. 1

FIG. 2

FIG. 1 is a front perspective view of a tape console showing my new design; and

FIG. 2 is a rear perspective view thereof.

The two sides of my design are identical. The dominant features of my design reside in the portions shown in full lines.

I claim:

The ornamental design for a tape console, as shown and described.
